ELECTRIC TROLLEY CONSTRUCTION

Ernest M. Glasgow, Towaco, N. J., assignor to
Feedrail Corporation, New York, N. Y., a corporation of New York

Application December 5, 1935, Serial No. 53,075

33 Claims. (Cl. 191—45)

This invention relates to electric trolley constructions of the type comprising bus bars and a carriage having contacts therefor, and more particularly to three phase installations of this character for distributing current to portable electric power tools.

This application is in part a continuation of my copending parent application Serial No. 12,530 filed March 22, 1935 claiming the novel conduit and bus bars, and combination thereof with the carriage; claims to the carriage per se having been divided out thereof and presented in this application together with improvements in the trolley.

The main objects of the present invention are to economize the manufacture, simplify the construction, and facilitate the installation and operation of constructions of this character, to provide a compact arrangement, and to protect the bus bars from short circuit and the carriage from obstruction.

Other objects and features of novelty will be apparent as the following description proceeds, reference being had to the accompanying drawings, in which

Figure 1 is a side elevation of the trolley construction according to the preferred embodiment of the present invention;

Figure 2 is an end elevation of the control box shown in Figure 1;

Figure 3 is a transverse vertical section taken along the line 3—3 of Figure 1; and showing the trolley carriage in end elevation;

Figure 4 is a vertical transverse section through the trolley carriage taken along the line 4—4 of Figure 7;

Figure 5 is an enlarged section similar to Figure 1, but showing the trolley carriage and side elevation;

Figure 6 is a plan of the trolley carriage;

Figure 7 is a vertical longitudinal section through the carriage taken along the line 7—7 of Figure 6;

Figure 8 is a view similar to Figure 6 showing an improved form of carriage;

Figure 9 is a section taken along the line 9—9 of Figure 8;

Figure 10 is a section taken along the line 10—10 of Figure 9;

Figure 11 is a section taken along the line 11—11 of Figure 8.

The electric trolley construction comprises an insulating member having bus bars secured thereto and complementary conduit members mounted at each side thereof, forming a conduit inclosing the bus bars, but spaced therefrom. The conduit contains a carriage according to the preferred embodiment of the present invention which moves longitudinally therein, and is provided with contacts engaging the bus bars,

The conduit is manufactured in sections or units, which are adapted to be joined in end to end relation to form a continuous conduit of a length to suit the installation.

Referring more particularly to the drawings, as shown in Figure 3 an insulating member 2 is provided, which may be conveniently molded of Bakelite, but may be constructed as desired from any other insulating material. The opposite sides and the edge of the member 2 are provided with undercut grooves 3, 4 and 5. These grooves receive bus bars 6, 7 and 8 respectively.

The preferred form of the bus bar comprises a strip of copper or other conducting material having its side edges bent back upon itself as at 10 and 11. The side edges are brought together as at 12 and then both are flared outwardly forming diverging flanges 13 and 14. The metal of these bus bars is resilient and hence the flanges 13 and 14 have a spring action which facilitates their longitudinal insertion in the undercut grooves 3, 4 and 5.

The margin of the insulating member 2 is secured between complementary conduit members 15 and 16. In the form shown the insulating member 2 has an upper margin 17 of reduced thickness and the side members 15 and 16 have vertical flanges 18 between which the margin 17 is secured. The conduit members 15 and 16 have side walls parallel to the insulating member 2 and terminating in inwardly directed flanges 19. The inner edges of the flanges 19 are spaced apart thus leaving the trolley slot 20. The flanges 19 adjacent the slot 20 are provided with reinforcing grooves or channels 21.

The trolley carriage which operates in the conduit just described is best shown in Figures 5, 6 and 7. This carriage is provided with a pair of trolley contacts 26 and 27 which respectively engage the bus bars 6 and 7, and a trolley contact 28 which engages the bus bar 8.

These contacts are preferably wheels, respectively journaled in U-shaped arms 30, which are pivotally mounted on an insulating plate 31, preferably of Bakelite, on the carriage. The arms for the contacts 26 and 27 are respectively pivoted on the upper ends of posts 32 and are urged toward each other by springs 33. The lower ends of these posts pass through the plate 31 and are threaded to receive nuts 34. Pins 35 in a groove 36 in the plate 31 prevent the posts 32 from turning.

The arm for the contact 28 is pivoted on a pin 38 carried by ears 39 depending through a slot 40 in the plate 31, from a clip 41 secured to the top of the plate 31 by a bolt 42. A spring 43 urges the arm 30 upward to project the contact 28 through the slot 40. Insulated wires 44 are respectively connected by nuts 45 to the threaded ends of the posts 32 and bolt 42.

The frame of the carriage is a box like structure, preferably formed from a single piece of sheet metal. Central vertical depending loops 46 join laterally extending floor flanges 47, from which side flanges 48 extend vertically.

As shown in Figure 5, a central portion of the carriage plate between the loops 46 is cut away, forming an aperture 49 through which the wires 44 depend. The loops 46 at each end are slotted to receive eyes 50 which are pivoted on pins 51 carried by the loops. A control box 52 as shown in Figures 1 and 2 is suspended from the eyes 50 and contains a switch, circuit breaker, and/or fuses. In order that different tools may be used interchangeably, a receptacle 53 is mounted in the box 52, under a hinged cover 54, to receive a plug 55. The box 52 is preferably constructed to provide an eye 56, on which the tool may be suspended when not in use.

As shown in Figure 4, the insulating plate 31 is secured to the carriage by screws 57 engaging posts 58 secured to the flanges 47. The corners of the plate 31 are cut away at 59 to clear the carriage supporting wheels 60. These wheels 60 rotate on axles 61 passing through the carriage side plates 48, and through vertical flanges 62 of box like clips 63 which are riveted to the top of floor flanges 47. Rubber blocks 65 in these clips bear against the axles 61, forming bumpers for the carriage.

Guide rollers 66 are mounted in slots 67 cut in the sides of the loops 46 and rotate on vertical pins 68 extending between horizontal channel clips 69 which connect the sides of the loop. Lugs 70 on these channels pass through the sides 47 and are peened over as shown in Figure 5.

To insert the trolley carriage in the conduit, the latch members 84 are caused to compress the springs 95 to release the hinged portions 92 which are swung upward. The carriage is then inserted, with the trolley contact 28 aligned with the lower edge bus bar 8. The posts 32 extend up on each side of the insulating member 2. As this Bakelite bus bar support is tapered at its lower portion, the trolley contacts 26 and 27 are spread thereby, against the action of their springs 33. When the hinged portions 92 are relatched, the edges of channels 21 engage the guide rollers 66 with a slight clearance, and the flanges 19 therebeyond pass under the supporting wheels 60 and form a track therefor. This condition may also be obtained by moving the carriage along into the rigid portion of the conduit section before the movable portion is replaced.

The improved form of trolley carriage shown in Figures 8, 9, 10 and 11 is provided with a pair of trolley contacts 26a and 27a adapted to respectively engage the bus bars 6 and 7 and a trolley contact 28a adapted to engage the bus bar 8.

The contacts 26a, 27a and 28a are blocks or lugs forming solid brushes of copper or other brush material respectively journaled in U-shaped arms 30a, which are pivotally mounted on an insulating base 31a preferably of Bakelite and asbestos composition, or other molded insulation, on the carriage. This base 31a has two upstanding ridges 96 and 97, and a slot 40a therebetween.

The arms for the contacts 26a and 27a are respectively pivoted on the upper ends of posts 32a and urged toward each other by springs 33a coiled about the posts and having one end hooked over the arm and the other end engaging a stop pin 36a. Stop plates 35a prevent the posts from

turning. These posts extend down through the ridges 96 and 97 which firmly support the same, and extend below the base 31a and are threaded to receive nuts 34a.

5 The arm for the contacts 28a is pivoted on a pin 38a carried by ears 39a depending through the slot 40a, from a clip 41a secured to the top of the base 31a between the ridges 96 and 97, by a bolt 42a. A spring 43a urges the arm 30a upward 10 to project the contact 28a through the slot. Insulated wires 44a are respectively connected by nuts 45 to the threaded ends of posts 32a and bolt 42a. The base 31a has a depending flange 76 which forms a longitudinal side conduit for the wire 15 44a leading to the contact 28a.

The brushes or lugs of this modification are all prevented from rotation, and are urged to parallelism with the bus bar surfaces, by leaf springs 98. These springs have one end hooked 20 under the bridge of the arms 30a and pass over the pivots and springs thereon, and have a reversely bent portion underlying the lugs 26a, 27a and 28a.

It should be noted that each brush 26a, 27a, 25 and 28a has a pigtail 99 of flexible stranded wire soldered directly thereto. For example, each of these lugs has a hole drilled in its rear face, and the end of the pigtail is soldered therein, as at 31. From this soldered connection, the pigtail 20 extends directly to a soldered terminal 13 for the binding post for the lead in wire 44a, such as those formed by the lower ends of the posts 32a. As shown, the pigtail 99 passes from the soldered 35 joint 11 over the spring 98 and through a hole 72 in the rear bridge of the arm 30a, and thence to the binding post. With this arrangement there is a direct electrical connection to the brush, in that there are no pivotal or rotating parts in the circuit between the lead in wires and the bus bar 40 contact, to cause arcing and pitting, and yet the pigtail is of sufficiently flexible construction to permit the play desired for free movement of the trolley.

The frame of this carriage is a box-like structure, preferably formed from a single piece of sheet metal. Central vertical depending loops 46a join laterally extending floor flanges 47a, from which side flanges 48a extend vertically. The base 31a is offset to overlie the upper edges 50 of these flanges, except at the ends, where ears 15 project upwardly from one flange only, to engage an internal projection inside the conduit, also on one side only, to prevent reverse insertion of the carriage. An insulating liner 77 is fitted inside the floor and side flanges and has an aperture 78 for the wires 44a.

As shown in Figures 8 and 11, the insulating base is secured to the carriage by screws 57a let down in countersunk portions 58a in the ridges 96 and 97 and suitably engaging the carriage plate. Corners of the plate are cut and folded to form flanges 62a having journals for axles 61a on which are mounted supporting wheels 60a.

63 Similar cutting and folding at the loops 46a forms flanges 68a for mounting for vertical guide rollers 66a, and rubber blocks 65a are fitted in the ends of these loops.

From the foregoing description it will be readily apparent that the construction according to the present invention is unusually compact, as the bus bars are close together although well insulated. The carriage also is small and compact which permits it to be housed by the conduit. The conduit having only the necessary

trolley slot protects the bus bars from short circuit, and prevents obstruction of the track for the carriage supporting wheels.

The invention is not limited to the details disclosed, but includes such embodiments as fall within the scope of the following claims.

I claim:

1. In an electric trolley construction, a carriage having a set of four supporting rollers arranged in transversely spaced pairs, a frame having journals for said supporting rollers, insulation supported by said frame, a set of three electrical trolley contacts on said carriage separate from said supporting rollers and insulated therefrom, means for urging a pair of said contacts toward each other and means for urging the third toward said pair.

2. In an electric trolley construction, a carriage having supporting rollers, three trolley contacts on said carriage separate from said supporting rollers and insulated therefrom, and means for urging each of said contacts radially toward a line parallel to the direction of movement of said carriage.

3. In an electric trolley construction, a carriage, having supporting rollers, three trolley contacts mounted on said carriage separate from said supporting rollers, means for insulating said contacts from said carriage, and means for urging said contacts each in a different direction toward a line extending in the direction of movement of said carriage.

4. In a three phase electric trolley construction, a carriage having supporting rollers, three trolley contacts each separate from said supporting rollers mounted for swinging movement on said carriage, means for insulating said contacts from said carriage, means for urging a pair of said contacts each toward the other, and means for urging the third contact toward said pair, the urging means for said pair being adapted to yield laterally to permit to pass therebetween into respective engagement with the three contacts a group of three bus bars along which said contacts may be moved by said carriage.

5. In an electric trolley construction, a carriage having a base of insulating material with upstanding pedestals, trolley contacts mounted on pivots extending upward from said pedestals, means for urging said contacts horizontally toward each other about said pivots, a third contact pivoted on said base, and means for urging said contact toward the other two in a vertical plane between said pedestals, said carriage, pedestals and contacts being constructed and arranged to leave an unobstructed longitudinal passage between said horizontally urged contacts.

6. In an electric trolley construction, for use in a conduit having bus bars therein and a longitudinal slot, a carriage having a base of molded insulating material with upstanding longitudinal ridges, supporting wheels for said carriage on which it may move in and along said conduit, trolley contacts mounted on said ridges, means for urging said contacts toward each other, a third contact pivoted on said base, and means for urging said third contact upwardly in a plane between said ridges.

7. In an electric trolley construction, a carriage having a base of insulating material with upstanding pedestals and a slot through said base therebetween, trolley contacts mounted on pivots carried by said pedestals, means for urging said contacts toward each other, a third contact piv-

oted on said base, and means for urging said third contact up through said slot.

8. In an electric trolley construction, a carriage having a base of molded insulating material with upstanding ridges, and a slot through said base therebetween, trolley contacts mounted on said ridges, means for urging said contacts toward each other, a third contact on said base adjacent said slot, and means for urging said third contact upwardly in a plane between said ridges.

9. In an electric trolley construction, for use in a conduit having bus bars therein and a longitudinal continuous slot, a carriage having a base of insulating material and wheels thereon for supporting said carriage in said conduit, said carriage having a portion depending through said slot, and a box suspended from said depending portion for connection to a portable electric tool and by means of which said carriage may be propelled along said conduit, arms pivotally mounted on said carriage within said conduit, brush blocks mounted on said arms, means for respectively urging each of said arms toward the others to engage its brush block with one of said bus bars, and a flexible metallic conductor directly connected to each of said brush blocks and extending therefrom through said slot to said connection box, whereby pivotal or rotary movement in the electrical connection from said brushes to said box is avoided.

10. In an electric trolley construction, for use with a conduit comprising a central group of side and edge bus bars, and side walls spaced from said bus bars and having inwardly directed flanges spaced apart to form a slot, a carriage, supporting means on said carriage for engaging said flanges for longitudinal movement therealong, trolley contacts on said carriage and insulated therefrom, means for urging a pair of said contacts toward each other for engagement with the side bus bars, means for urging another of said contacts into engagement with the edge bus bar, and electrical conductors connected to said contacts and insulated from said carriage and adapted to pass through the conduit slot for distributing current from its bus bars.

11. In an electric trolley construction, for use with a conduit having bus bars therein and a longitudinal continuous slot, a carriage having a base of molded insulating material with upstanding longitudinal ridges and a slot through said base therebetween, brushes respectively adapted to slide along the conduit bus bars, arms supporting a pair of said brushes mounted on pivots extending upward from said ridges, means for urging said pair of brushes toward each other, means pivoted on said base adjacent said slot for supporting a third brush, means for urging said third brush upwardly through said slot, a frame for said base having wheels for supporting said carriage in the conduit and a portion depending through the conduit slot and a box suspended from said depending portion for connection to a portable electric tool and by means of which said carriage may be pulled along with said tool, and a flexible electric conductor directly connected to each of said brushes and extending therefrom through the conduit slot to said connection box.

12. For use with a conduit having an elongated slot and bus bars mounted in said conduit and insulated therefrom, a carriage adapted to be supported in said conduit for movement therealong, trolley contacts on said carriage and in-

sulated therefrom, means for urging said contacts into respective engagement with said bus bars, and a polarizing projection on one side only of said carriage said carriage comprising a side flange and said polarizing projection comprising an ear formed of an extension of said side flange.

13. In a carriage for an electric trolley construction, a frame having a metal floor and a central depending portion, an insulating base overlying said floor and secured thereto on both sides of said central depending portion, supporting rollers having transverse journals above said floor, and current collectors carried by said base between the vertical planes of said supporting roller journals, said base having an aperture therein, said floor having an insulating liner, and one of said collectors having supporting means between said base and liner and including spring means projecting said collector through said aperture.

14. In a carriage for an electric trolley construction, a frame having a sheet metal floor and a depending central portion, an insulating base extending over said floor, current collector supporting means housed between said frame and insulation and including spring means, said insulation having aperture means therein, and collector contact means carried by said supporting means and projected through said aperture means by said spring means, said aperture being formed in a flat portion of said insulating means which is perpendicular to the path of movement of said collector contact means passing through said aperture, and said aperture conforming to the cross section of the collector means passing therethrough but having a clearance therefor, and supporting rollers having journals in said frame above the bottom of said base, guide rollers journaled within said central portion, an electrical device suspended by said central portion, and conductors connecting said collector contact means and said suspended device.

15. A carriage for an electric trolley construction, comprising a metal frame having floor parts and a central depending portion, said carriage having journals for supporting rollers, an insulating base extending over said floor parts and secured thereto on each side of said central portion, current collectors carried by said insulating base, and a control box carried by said depending portion and connected to said collectors said control box containing circuit protective means and receptacle means in circuit with said collectors, said box having a hinged cover and at least one of said means mounted under said hinged cover and accessible from outside said box only when said cover is opened, said receptacle means being adapted to secure a plug, whereby different tools may be used interchangeably with the same carriage.

16. In an electric trolley construction, an insulating base, vertical posts supported by said base and extending thereabove, arms pivoted on said posts, springs urging said arms about said posts toward each other, another arm pivoted on said base, a spring urging said arm upward toward the others, a frame having a central depending portion and a sheet metal floor underlying said base and secured thereto on each side of said central portion, supporting rollers having transverse journals above said floor near each end, an electrical device suspended by said central depending portion, current collector brushes carried by said pivoted arms between the verti-

cal planes of said supporting roller journals, and conductors directly connecting said brushes to said suspended device.

17. A trolley collector carriage part comprising horizontal flanges which have their outer portions flanged upwardly to provide vertical flanges, horizontally disposed axles above the horizontal flanges and journaled supporting rollers which depend through slots of the horizontal flanges, and rubber bumper blocks at the ends of the carriage, in alignment with the horizontal axles, and seated on the horizontal flanges and between the vertical flanges.

18. A T shaped elongated trolley collector carriage part comprising a U cross section vertical portion and upper portions extending transversely thereabove to provide horizontal flanges, horizontally disposed axles above the horizontal flanges and journaled supporting rollers which depend through slots of the horizontal flanges, and rubber bumper blocks at the ends of the carriage, and seated between the sides of said central vertical portion.

19. A trolley collector carriage frame comprising a sheet metal floor having lateral extensions turned up to form side flanges, and supporting rollers journaled between said side flanges and projecting through slots in said floor.

20. A trolley collector comprising a frame having longitudinally and transversely spaced supporting rollers and loops of sheet metal strap depending centrally with respect to said supporting rollers, insulating material overlying said frame and secured thereto on both sides of said loops, longitudinally extending pins in said loops, a control box depending from said pins and having transverse end walls and a transversely opening tool supporting eye therebelow, and a receptacle mounted in said control box between said transverse end walls and adapted to receive a plug for the tool supported by said eye.

21. In a carriage for an electric trolley construction, a frame having a sheet metal floor and a central depending portion, an insulating base overlying said floor and secured thereto on both sides of said central depending portion, supporting rollers having transverse journals above said floor, and current collectors carried by said base between the vertical planes of said supporting roller journals.

22. In a carriage for an electric trolley construction, a frame having a sheet metal floor and a depending central portion, an insulating base extending over said floor and supporting rollers having journals in said frame above the bottom of said base, guide rollers journaled within said central portion, an electrical device suspended by said central portion, current collectors carried by said base and conductors connecting said collectors and said suspended device.

23. A carriage for an electric trolley construction, comprising a sheet metal frame having floor parts and a central depending portion, said floor parts having journals for supporting rollers, an insulating base extending over said floor parts and secured thereto on each side of said central portion, current collectors carried by said insulating base, and a control box carried by said depending portion and connected to said collectors.

24. A T shaped elongated trolley collector carriage part comprising a U cross section vertical portion having its upper portions flanged away from each other horizontally to provide hori-

zontal flanges, horizontally disposed axles above the horizontal flanges and journaling supporting rollers which depend through slots of the horizontal flanges, and horizontally disposed pins in the bight of the vertical portion providing pivotal mountings.

25. A T shaped elongated trolley collector carriage part comprising a U cross section vertical portion and upper portions extending away from each other to provide horizontal flanges, horizontally disposed axles adjacent the horizontal flanges and journaling supporting rollers which project through slots of the horizontal flanges, vertically disposed axles within the carriage and journaling side thrust rollers which extend through slots of vertical parts of the carriage, and horizontally disposed pins in the bight of the vertical portion providing pivotal mounting means, the supporting rollers, the thrust rollers, and the pins being symmetrically arranged with respect to one another to prevent rocking of the carriage.

26. A T shaped elongated trolley collector carriage part formed of one piece and comprising a U cross section vertical portion having its upper portions flanged away from each other horizontally to provide horizontal flanges which have their free end portions in turn flanged upwardly to provide vertical flanges, horizontally disposed axles above the horizontal flanges and journaling supporting rollers which project through slots of the horizontal flanges, vertically disposed axles within the carriage and journaling side thrust rollers which project through slots of vertical parts of the carriage, and horizontally disposed pins in the bight of the vertical portion providing pivotal mountings for a tool support and accessible through cutouts of said bight.

27. A T shaped elongated trolley collector carriage part formed of one piece and comprising a U cross section vertical portion having its upper portions flanged away from each other horizontally to provide horizontal flanges which have their free end portions in turn flanged upwardly to provide vertical flanges, horizontally disposed axles above the horizontal flanges and journaling supporting rollers which project through slots of the horizontal flanges, vertically disposed axles within the carriage and journaling side thrust rollers which project through slots of vertical parts of the carriage, and horizontally disposed pins in the bight of the vertical portion providing pivotal mountings for a tool support and accessible through cutouts of said bight, the supporting rollers, the thrust rollers, and the tool supporting pins being symmetrically arranged with respect to one another to prevent rocking of the carriage, and rubber bumper blocks at the ends of the carriage, in horizontal alignment with the horizontal axles, and seated on the horizontal flanges and between the vertical flanges.

28. A trolley collector carriage comprising a pair of longitudinally extending plates having their upper portions flanged away from each other, transversely spaced supporting rollers journaled in said carriage, an insulated base secured to said upper flanged portions, collector contacts carried by said insulated base, and a pair of longitudinally spaced trough-like loops connecting the lower portions of said plates and depending between said transversely spaced supporting rollers.

29. In an electric trolley construction, a carriage comprising a frame and an insulating cover, collector contact supporting means housed between said frame and cover and including spring means, said cover having aperture means therein, and collector contact means on said supporting means and projected through said aperture means by said spring means, the outer margin of said cover engaging a coextensive portion of said frame and enclosing said collector contact means.

30. In an electric trolley construction, a chassis comprising a frame and spaced layers of insulation one above the other, collector contact supporting means housed between said layers, spring means located above said frame and below said upper layer, said upper layer having aperture means formed therein, and collector contact means carried by said supporting means and projected through said aperture means by said spring means, the outer margin of said upper layer engaging a coextensive portion of said frame and enclosing said collector contact means.

31. In an electric trolley construction, a sheet metal floor having upstanding side flanges and pivot supports depending from the front and rear parts of said floor, insulating layers above said floor and maintained in spaced relation, collector contact supporting means housed between said spaced layers, the side margins of said upper layer engaging the upper margins of said side flanges, said upper layer having aperture means formed therein, collector contact means carried by said supporting means, and means for urging said collector contact means up through said aperture means.

32. In an electric trolley construction, a chassis comprising a floor and upstanding side flanges, longitudinally and transversely spaced supporting rollers journaled on said chassis, said chassis having a central sheet metal portion depending from said floor and carrying pivoted supports, and spaced layers of insulation one above the other, the side margins of said upper layer engaging the upper margins of said side flanges, collector contact supporting means housed between said layers, spring means located above said floor and below said upper layer, said upper layer having aperture means formed therein, and collector contact means carried by said supporting means and projected through said aperture means by said spring means, said aperture means being formed in a flat portion of said upper layer which is perpendicular to the path of movement of said collector contact means passing therethrough.

33. A carriage for an electric trolley construction, a frame having a sheet metal floor having floor parts and a central depending portion, comprising longitudinally spaced and aligned loops of U shape cross section, hinge pins in said loops, said floor parts having journals for supporting rollers, an insulating base extending over said floor parts and supported on said frame with at least the main body portion of the base in spaced relation with the floor, current collectors carried by said insulating base, at least one of said collectors having at least a portion below said base, and a control box carried by said depending portion and connected to said collectors.
